By his Attorneys,

Inventor
Henry W. Chase,

C. A. Howes & Co.

UNITED STATES PATENT OFFICE.

HENRY W. CHASE, OF WITTENBERG, WISCONSIN.

DOOR-SECURER.

SPECIFICATION forming part of Letters Patent No. 463,226, dated November 17, 1891.

Application filed August 15, 1891. Serial No. 402,729. (No model.)

To all whom it may concern:

Be it known that I, HENRY W. CHASE, a citizen of the United States, residing at Wittenberg, in the county of Shawano and State 5 of Wisconsin, have invented a new and useful Door-Securer, of which the following is a specification.

The invention relates to improvements in door-securers.

10 The object of the present invention is to provide a simple, strong, and inexpensive door-securer adapted to be readily carried and capable of being conveniently and quickly applied to a door and of preventing the 15 same being opened by force from the exterior.

The invention consists in the construction and novel combination and arrangement of parts hereinafter fully described, illustrated 20 in the accompanying drawings, and pointed out in the claims hereto appended.

In the drawings, Figure 1 is a perspective view of a door-securer constructed in accordance with this invention and shown applied 25 to a door. Fig. 2 is a vertical longitudinal sectional view of the lever being raised. Fig. 3 is an elevation showing the parts folded for carrying.

Referring to the accompanying drawings, 30 1 designates a plate or casing adapted to fit against a door and provided at its lower end with a lip 2, arranged to fit in the crank at the bottom of the door and provided at its sides with longitudinal flanges 3, between 35 which is pivoted one end of a lever 4, which has pivoted to it one end of a brace 5. The lever 4 is U-shaped and has a longitudinal opening 6 and tapers in thickness toward its outer end, and the brace 5 also tapers and increases in thickness toward its end 7, which 40 is pivoted in the opening a short distance from the pivot 8, which fulcrums the lever on

the casing 5. The brace 5 is designed to engage the floor to prevent the door being forced open, and the lever 4, by being U-shaped— 45 that is, having the longitudinal opening—and tapering in thickness, is enabled to lie flat against the brace and form with it a straight brace to prevent the door being forced open. When the lever 4 is raised, the straight brace 50 is broken, and the brace 5 has its upper end lifted and it is withdrawn from engagement with the floor. The outer or lower end of the brace is enlarged and is provided with a series of teeth 9 to enable it to readily engage 55 the floor.

It will be seen that the device is simple, strong, and durable, is adapted to be conveniently carried, and is capable of being readily applied to a door and of preventing the latter being forced inward.

What I claim is—

1. A door-securer comprising a plate provided at its lower end with a lip adapted to fit in the crank at the bottom of the door, a 65 lever having one end fulcrumed on the plate, and a brace having its outer end adapted to engage the floor and having its inner end pivoted to the lever, substantially as described.

2. A door-securer comprising a plate provided at one end with a lip and having longitudinal flanges, a lever having a longitudinal opening and having one end pivoted between said flanges, and a brace adapted to engage the floor and having one end pivoted 75 in the opening of the lever, substantially as described.

In testimony that I claim the foregoing as my own I have hereto affixed my signature in presence of two witnesses.

HENRY W. CHASE.
